CLAIM

The ornamental design for handles for a butterfly knife, as shown and described.

DESCRIPTION

FIG. 1 is a front elevation view of handles for a butterfly knife, showing my new design in a closed position, the broken lines representing environment and forming no part of my claimed design;

FIG. 2 is a top plan view of the invention illustrated in FIG. 1;

FIG. 3 is a rear elevation view of the invention illustrated in FIG. 1;

FIG. 4 is a bottom plan view of the invention illustrated in FIG. 1;

FIG. 5 is a right end elevation view of the invention illustrated in FIG. 1;

FIG. 6 is a left end elevation view of the invention illustrated in FIG. 1;

FIG. 7 is a front elevation view of the invention illustrated in FIG. 1, shown in an open position;

FIG. 8 is a top plan view of the invention illustrated in FIG. 7;

FIG. 9 is a rear elevation view of the invention illustrated in FIG. 7; and,

FIG. 10 is a bottom plan view of the invention illustrated in FIG. 7.
